John E. Carl

United States Patent Office.

F. B. MORSE, OF PLANTSVILLE, CONNECTICUT, ASSIGNOR TO HIMSELF
AND H. D. SMITH & CO., OF SAME PLACE.

Letters Patent No. 96,255, dated October 26, 1869.

IMPROVED BOLT FOR WHIFFLETREES.

The Schedule referred to in these Letters Patent and making part of the same.

To all whom it may concern:

Be it known that I, F. B. MORSE, of Plantsville, in the county of Hartford, and State of Connecticut, have invented a new Improvement in **T**-Bolt for Whiffletrees; and I do hereby declare the following, when taken in connection with the accompanying drawings, and the letters of reference marked thereon, to be a full, clear, and exact description of the same, and which said drawings constitute part of this specification, and represent, in—

Figure 1, a side view,

Figure 2, a top view, and in

Figure 3, an under-side view of the **T**.

This invention relates to an improvement in the bolts which are employed to secure the whiffletree to carriages.

Heretofore the **T** of the bolt has been made pointed at both ends, and then the end bent down, so as to turn into the wood, which gives to the end an unfinished appearance; the object of turning down the ends being to hold the head in its place and prevent the bolt from turning while the nuts are being screwed on to the lower end.

The object of my invention is to construct the head with both ends sharp and finished, and yet provided with means of holding the same in position better and stronger than bolts as heretofore constructed.

To enable others skilled in the art to make and use my invention, I will proceed to describe the same, as illustrated in the accompanying drawings.

A is the bolt.

B, the head, which is of oval shape, and extending from the bolt in opposite directions, so as to form a longitudinal plate or bar upon the top of the whiffletree, and when the bolt is placed through the whiffletree, it will lie longitudinally thereon.

At each end of the head, and upon the under side, I form a fin or thin lip, **a**, projecting downward, as seen in figs. 1 and 3, and this I do by forming a corresponding recess in the die in which the head of the bolt is formed, so that the said fins are formed in the process of striking up the bolt-head.

These fins are driven into the wood of the whiffletree, and while they serve to prevent the bolt from turning, they at the same time strengthen the end of the head, and prevent its bending up from the whiffletree.

As an article of manufacture, the bolt is sent to the trade without being threaded, that is, as shown in the drawings.

Having fully described my invention,

What I claim as new and useful, and desire to secure by Letters Patent, is—

As an improved article of manufacture, the herein-described whiffletree-bolt, the head **B** having fins **a** formed at the end, upon the under side of the head, substantially as and for the purpose set forth.

F. B. MORSE.
